SET OF PLAYING CARDS

William D. Lee, Chevy Chase, Md.

Application September 4, 1956, Serial No. 42,821

Term of patent 14 years

(Cl. D34—13)

Fig. 1

Fig. 3

Figures 1, 2, and 3 are face views of the set of playing cards showing my new design.

The backs of the cards are all alike and are of conventional design.

I claim:

The ornamental design for a set of playing cards, as shown and described.
